ATTACHMENT FOR HOLDING CROSS BRACES TO END FRAME SCAFFOLDING

Victor W. Meng, New Hyde Park, N. Y., and
Joseph Huck, Tenafly, N. J., assignors to The
Patent Scaffolding Co., Inc., Long Island City,
N. Y., a corporation of New York

Application June 28, 1949, Serial No. 101,896

1 Claim. (Cl. 304—40)

1

This invention relates to end frame scaffolding, in which a pair of integral end frames are supported by longitudinally disposed crossbraces.

The object of the invention is to provide means for holding the ends of the crossbraces against the uprights of the end frames, to take the place of the nuts for screw-threaded stems supported by said uprights, heretofore in general use.

It has been found that these relatively small nuts are easily lost. Also, the threads thereof rust, or are damaged by impact or careless application to the threaded stems, and in such cases are not properly applied, or not applied at all, thus leaving an end or two of the crossbraces subject to disengagement from the stems. As this type of scaffolding is of the built up type, that is, one end frame is placed vertically above an end frame below, often to considerable height, the security of such a built up structure is proportionate to its weakest link.

To overcome these objections, the invention contemplates an attachment applied to an upright of an end frame, which attachment preferably above a standard stem of an upright, has a pivoted yoke with an eyelet to pass over the stem, and has a pivoted link to hold the yoke down against the end of the crossbrace engaging the stem, the relationship of the yoke and link being such to provide toggle actions tending to hold the yoke in down position or in up position, until manually moved. Furthermore, in the preferred form of the yoke, a plurality of flat surfaces and intervening steps are provided on the outer surface of the yoke, to hold the engaging pin of the link in relatively permanent position.

The invention will be further described hereinafter, an embodiment thereof shown in the drawings, and the invention will be finally pointed out in the claim.

In the accompanying drawings,

Fig. 1 is a perspective view of a scaffold, as known, showing two end frames held in upright position by crossbraces, and having the attachment embodying this invention applied to the uprights of the end frames in proximity to the stems;

Fig. 2 is a partial perspective view of an upright and the attachment applied thereto;

Fig. 3 is a side view of Fig. 2;

Fig. 4 is a front view of Fig. 2;

Fig. 5 is a side view, but with the yoke and link in its upper position; and

Fig. 6 is a fragmentary diagrammatic view showing the relationship of the parts.

Similar characters of reference indicate corresponding parts throughout the various views.

2

Referring to the drawings, and more particularly to Figure 1, the end frame 10 of light weight tubular metal is joined to a like end frame 11, by lateral crossbraces 12 having their free ends 13 provided with holes 14 to fit over screw-threaded stems 15 secured to the uprights 16 of each end frame. In practice, nuts (not shown) engage these screwthreaded stems 15 to hold the apertured ends 13 of the crossbraces 12 against the uprights 16. The end frames 10 and 11 have a preferred design of horizontals and a vertical, but different designs of horizontals, verticals and in some cases, diagonals may be used, depending on the taste of the maker, or to some extent, upon the utility of these parts. No invention is claimed in this application in the collocation of such members.

Structures as described are known. The objection to the use of the threaded stems 15 is that very often one or more of the four nuts become misplaced in the assembly or disassembly of these structures, and also become inoperative by rusting or injury by impact on the threads of the stem or nut.

The improvement consists in the provision of a brace holding attachment 20 applied to the uprights 16. Each upright 16 of each end frame has two such attachments applied thereto, each in proximity to the stems 15 and preferably above the same.

Each attachment 20 consists of a supporting web 21 secured preferably by welding 22 to an upright 16. The web 21 has a hole therein for the passage of a bolt 23, the ends of which form shafts

24 for a yoke 25. The outer side of this yoke 25 has a cam surface 26 of special contour for the purpose to be described. The free end of the yoke 25 is formed into an eyelet end 27, with an intervening opening 28 for the passage of the

fixed stem 15 through the opening 28. The inner part of the end 27 abuts against or presses slightly against an end 13 of a crossbrace 12, when the same is applied.

Upon the web 21, a second pin 30 is provided, which, in the embodiment, passes through the web 21, and also has its ends 31 act as shafts for supporting and pivoting a U-shaped clamping member 32, formed of two parallel side members 33, and a cross-pin 34. The cross-pin 34 is spaced from the shaft 31 a suitable distance, to enable the cross-pin 34 to ride over the peak 35 of the cam portion 26, and to hold the yoke 25 in down position against an end 13 of a crossbrace 12, as shown in Figure 3.

The arc of movement 36 of the cross-pin 34 with the axis of the shafts 31 as a center of curvature,

is such that it intersects the cam surface at 37 (Fig. 6), and thus holds the yoke 25 in down position against the end 18 of the brace 12.

When the cross-pin 34 is moved into its upper position, its lateral side members 33 have their ends abut against the upright 16, and this permits the yoke 25 to be moved upwardly until the surface 38 of the yoke 25 abuts against the cross-pin 34 (Fig. 5).

When the yoke 25 is moved into its upper position, as shown in Fig. 5, it remains in that position until manually moved downward.

The lower end of the cam surface 26 is rounded as shown at 35. In the preferred embodiment, the outer surface of the yoke 25 below the 15 rounded part 35, is provided with a plurality of alternating flat surfaces and steps (Fig. 6). In a size, in which the distance between pivot 40 and the pressure point 41 of the yoke, is $3\frac{1}{2}$ in., the flat surface 42 adjacent the curved part 35 is 20 $\frac{1}{4}$ in., and is an angle of 52° to the horizontal; the step 43 adjacent the lowest end of the flat surface 42 is $\frac{3}{16}$ in. in length, and is substantially vertically disposed; the next flat surface 44 is $\frac{1}{4}$ in. at an angle of 30° ; the next step 45 is $\frac{3}{16}$ in. substantially vertical; and the next flat surface 46 is $\frac{3}{8}$ in. in length, at an angle of 18° to the horizontal. These dimensions are given as an example. The pin 34 cooperates with these flat surfaces and steps to the extent desired.

It will be seen that in either down or up position of the yoke there is a shifting of points of application in accordance with the laws underlying a toggle action.

We wish it to be understood that we do not 35 desire to be limited to the exact details of construction shown and described, for obvious modifications will occur to a person skilled in the art.

We claim:

In an attachment for holding a crossbrace to end frame scaffolding, in which each end frame has an upright and a stem on said upright, a cross brace on the stem, the combination of a web secured to said upright above said stem, said web being in a vertical plane and longitudinal of said upright, a first yoke having an end embracing said web, and pivoted thereto, and having its other end provided with a loop swingable to surround said stem, and with an abutment on its exterior, a second yoke embracing said first yoke and having one end embracing said web and pivoted thereto below the pivot of said first yoke, and a cross-pin on the other end of said second yoke for engaging said abutment, whereby when said second yoke engages said abutment, said loop surrounding said stem is held in engagement with the brace to hold the brace against the upright.
